[57] CLAIM

The ornamental design for a finger-contoured ring, as shown.

DESCRIPTION

FIG. 1 is a top plan view of a finger-contoured ring showing my new design, the bottom being a mirror image;

FIG. 2 is a right side elevational view thereof;

FIG. 3 is a front elevational view thereof;

FIG. 4 is a perspective view thereof;

FIG. 5 is a top plan view of a finger-contoured ring showing a second embodiment of my new design, the bottom being a mirror image;

FIG. 6 is a right side elevational view of FIG. 5;

FIG. 7 is a front elevational view of FIG. 5; and

FIG. 8 is a perspective view of FIG. 5.
